UNITED STATES PATENT OFFICE.

HOWARD EARL HOOVER, OF CHICAGO, ILLINOIS, ASSIGNOR TO HOOVER SUCTION SWEEPER COMPANY, OF NEW BERLIN, OHIO, A CORPORATION OF OHIO.

BRUSH FOR SUCTION-CLEANERS.

1,332,897.

Specification of Letters Patent.

Patented Mar. 9, 1920.

Application filed July 14, 1917. Serial No. 180,516.

To all whom it may concern:

Be it known that I, HOWARD EARL HOOVER, a citizen of the United States, residing at Chicago, in the county of Cook and State of Illinois, have invented a certain new and useful Improvement in Brushes for Suction-Cleaners, of which the following is a specification.

My invention relates to brushes particularly adapted for use in connection with suction cleaners. It is illustrated in the accompanying drawings wherein,

Figure 1 is a part end and sectional view of a vacuum cleaner with parts broken away 10 to show the brush in position;

Fig. 2 is an elevation of a detached brush; and

Fig. 3 is an elevation of a modified form 15 of brush.

Like parts are indicated by the same letter 20 in all the figures.

A is the case of a suction cleaner, B the fan by whose motion air is drawn in through the mouth C, past the brush D. The fan 25 and brush are driven in any desired manner by any form of mechanism, preferably an electric motor mounted on or within the casing. None of these details is of any importance in the present case so they are not 30 here illustrated.

E is a cylindrical brush body through which passes a shaft N, and this shaft is suitably mounted in any desired manner and preferably provided with thread guards F 35 for the bearings on the shaft within the cylindrical brush body.

G, G are a series of bosses on the brush. They may be formed in the casting, or they 40 may be separately formed and screwed in or otherwise attached to the cylindrical body. H, H are the bristles arranged in groups in these bosses.

J is a continuous spiral ridge projecting from the body of the brush and bristle 45 groups may be arranged therealong. If the body is heavy enough, the bunches of bristles might be attached thereto without bosses or ridges.

K is the driving pulley, preferably integral with the brush body and placed either 50 near the middle or at one end as may be desired, or as required by the design of the suction cleaner.

The groups of bristles are arranged in 55 one continuous spiral from end to end and

nearly entirely surrounding the brush body. The groups of bristles are placed so as to overlap in the longitudinal direction or so as to leave no unswept portion of the carpet or covering against which the brush is operated. If the pulley is between the ends of the body, then two such groups of bristles should be placed one on each side of the pulley and close thereto so that they may as nearly as possible bridge the space over 60 the pulley. If the pulley is placed at one end of the brush body, the last group of bristles at that end should be placed in close proximity to the pulley so as to overhang it as much as possible. The groups of 65 bristles should be uniformly spaced with respect to their distance from each other along the spiral line and with respect to their angular distance from each other. By such angular distance I mean the angle 70 made by the radii which pass through the axis of the brush and the centers of such groups of bristles. The spiral does not make a complete circle of the brush body, but the angular distance between the two 75 end groups is the same as the angular distance between any two adjacent groups.

The arrangement of the bristles in groups is of course only the preferred form, as they might be arranged in a solid continuous 80 spiral line, but such arrangement should be according to the principles above suggested.

This arrangement of the bristles whether 85 in groups or a continuous line, results in balancing the brush and giving it a constant 90 load. There is always one group of bristles or one section of bristles of a given size and only such group or section in contact with the surface to be cleaned. The work of the brush and of the motor is therefore uniform 95 and balanced so as to avoid irregularity of action. If bristle groups are used they must of course be placed closer together than if they were arranged in two or more spiral lines where the individual groups of successive groups may be staggered with reference to one another.

Another result from the use of such a brush in a suction cleaner is that it permits with a given brush rotation the use of a 100 high speed and therefore light and relatively cheap motor.

It will be understood, of course, that such 105 a brush has the double function of sweeping and vibrating or beating the carpet or 110

- floor covering, and since there is but one such beating or vibrating effect for each rotation of the brush, a relatively high speed motor may be employed, or a motor 5 with twice the speed of one used with a two spiral brush in order to have the same number of vibratory actions in a given time. This brush therefore permits the manufacture with a predetermined or established 10 number of vibrations to have a higher speed, lighter and cheaper motor.

We have not dwelt upon the details of the manufacture of the brush or of a suction cleaner or the several connected parts.

- 15 As previously suggested, I wish my drawings to be taken as diagrammatic, for while they do represent a substantially working form of device, nevertheless very material departures in size, construction or arrangement of the several parts or elements of parts might be made without departing from the spirit of my invention. I have only shown preferred forms.

The use and operation of my invention are 25 obvious from what has been already said. Such a brush when used in a suction sweeper may be suitably mounted in or near the mouth and is driven by a belt or other power transmission from the motor, which preferably also drives the fan. The brush is given a relatively high speed of rotation and is supported in such manner that the carpet or floor covering preferably drawn up to the mouth is both brushed and beaten by the 30 brush. A longitudinal section of the floor covering as it successively encounters a given group or section of bristles, receives a blow therefrom with every revolution and that blow is what gives the carpet the vibrating 35 effect. Such bristles also as they pass by, sweep the carpet, carrying away the dirt which is raised by the vibration.

The particular arrangement of the bristles or groups of bristles as shown is 40 designed to balance the brush and motor, but of course if that were unimportant, the single spiral could have a travel equal to a circle.

I claim:—

- 50 1. A brush comprising a body and arranged radially thereabout perpendicular to the axis of rotation from end to end, a single spiral row of bristles approximately encircling the body and means whereby said brush body is adapted to be rotatably mounted.

2. A brush comprising a body and arranged radially thereabout perpendicular to the axis of rotation, a single spiral row of 55 bristles whose travel is less than a circle by an amount equal to the distance between adjacent tufts of bristles.

3. A brush comprising a body and arranged radially thereabout perpendicular to the axis of rotation from end to end a

single spiral row of bristles approximately encircling the body, said bristles arranged in groups and means whereby said brush body is adapted to be rotatably mounted.

4. A brush comprising a body and arranged radially thereabout perpendicular to the axis of rotation from end to end a single spiral row of bristles whose travel is less than a circle by an amount equal to the distance between adjacent tufts of bristles, said 75 bristles arranged in groups.

5. A brush comprising a body and arranged radially thereabout perpendicular to the axis of rotation from end to end a single spiral row of bristles approximately encircling the body, said body provided with a driving belt pulley and the bristles arranged in close proximity thereto so as to overhang such pulley and means whereby said brush body is adapted to be rotatably 85 mounted.

6. A brush comprising a body and arranged radially thereabout perpendicular to the axis of rotation from end to end a single spiral row of bristles whose travel is less 90 than a circle by an amount equal to the distance between adjacent tufts of bristles, said body provided with a driving belt pulley and the bristles arranged in close proximity thereto so as to overhang such pulley.

7. A brush comprising a body and arranged radially thereabout perpendicular to the axis of rotation from end to end a single spiral row of bristles approximately encircling the body, said bristles arranged in 100 groups, said body provided with a driving belt pulley and the bristles arranged in close proximity thereto so as to overhang such pulley and means whereby said brush body is adapted to be rotatably mounted.

8. A brush comprising a body and arranged radially thereabout perpendicular to the axis of rotation from end to end a single spiral row of bristles whose travel is less than a circle by an amount equal to the distance between adjacent tufts of bristles, said 110 bristles arranged in groups, said body provided with a driving belt pulley and the bristles arranged in close proximity thereto so as to overhang such pulley.

9. A brush comprising a body and a single row of bristles approximately encircling the body arranged radially perpendicular to the axis of rotation from end to end in contiguous groups, the angular distance between the first and last group being approximately the same as the angular distance between any two adjacent groups and means whereby said brush body is adapted to be rotatably mounted.

10. A brush comprising a body and a single row of bristles approximately encircling the body arranged radially perpendicular to the axis of rotation from end to end in contiguous groups, the angular distance between the 120 125 130

first and last group being approximately the same as the angular distance between any two adjacent groups, and a driving belt pulley on the brush body with bristles adjacent thereto so as to overhang the pulley and means whereby said brush body is adapted to be rotatably mounted.

11. The combination with a suction cleaner having an open-mouthed suction 10 nozzle, of a brush mounted for rotation therein comprising a brush body, and arranged radially thereabout from end to end, a single spiral row of bristles approximately 15 encircling the body.

12. The combination with a suction cleaner having an open-mouthed suction nozzle, of a brush mounted for rotation therein comprising a brush body, and arranged radially thereabout from end to end, 20 a single spiral row of bristles approximately

encircling the body, and a motor mounted on the cleaner and means whereby the brush is driven from the motor.

13. The combination with a suction cleaner having an open-mouthed suction 25 nozzle, of a brush body mounted for rotation therein, a motor mounted on the cleaner, a fan contained in the cleaner, means whereby the brush and fan are driven from the motor, said brush body having arranged radially thereabout from end to end a single spiral row of bristles approximately encircling the body.

In testimony whereof, I affix my signature in the presence of two witnesses this 2nd day 35 of July 1917.

HOWARD EARL HOOVER.
